[57] **CLAIM**

I claim the ornamental design for a cover for toilet plunger, as shown and described.

DESCRIPTION

FIG. 1 is a front, top and side perspective view of the cover for toilet plunger embodying the design of the present invention.

FIG. 2 is a front view in elevation thereof.

FIG. 3 is a left side view thereof, the side opposite being a mirror image of the side shown in FIG. 3.

FIG. 4 is a bottom plan view thereof.

FIG. 5 is a top plan view thereof; and,

FIG. 6 is a rear view in elevation thereof.
